US00D752556S

(12) **United States Design Patent**
Eriksen

(10) **Patent No.:** US D752,556 S
(45) **Date of Patent:** ** Mar. 29, 2016

(54) **HAND CONTROL**

- (71) Applicant: **LINAK A/S**, Nordborg (DK)
- (72) Inventor: **Christian Brunn Eriksen**, Sønderborg (DK)
- (73) Assignee: **Linak A/S**, Nordborg (DK)
- (**) Term: **14 Years**
- (21) Appl. No.: **29/511,422**
- (22) Filed: **Dec. 10, 2014**

Related U.S. Application Data

- (62) Division of application No. 29/478,491, filed on Jan. 6, 2014, now Pat. No. Des. 728,531.

(30) **Foreign Application Priority Data**

- Jul. 6, 2013 (DK) ..... DA 2013 00047
- (51) **LOC (10) Cl.** **14-03**
- (52) **U.S. Cl.** **D14/218**

(57) **CLAIM**

The ornamental design for a hand control, as shown and described.

DESCRIPTION

FIG. 1 is a top perspective view of a hand control according to my new and ornamental design,

FIG. 2 is a bottom perspective view thereof,

FIG. 3 is a top plan view thereof,

FIG. 4 is a bottom plan view thereof,

FIG. 5 is a left side view thereof,

FIG. 6 is a right side view thereof,

FIG. 7 is a front end view thereof; and,

FIG. 8 is a rear end view thereof.

The broken line showing of indicia on the buttons is included for the purpose of illustrating portions of the hand controller that form no part of the claimed design.

1 Claim, 2 Drawing Sheets
